(57) **CLAIM**

The ornamental design for an inflatable water hammock as shown and described.

DESCRIPTION

FIG. 1 is a front perspective view of an inflatable water hammock, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view thereof; taken from the encircled portion 9 in FIG. 1.

The dash-dot-dash broken lines in the drawings are included to indicate a partially enlarged view and form no part of the claimed design.

1 Claim, 9 Drawing Sheets
